UNITED STATES PATENT OFFICE.

GUSTAV BISSINGER, OF AUGSBURG, BAVARIA, ASSIGNOR TO MASCHINEN-FABRIK AUGSBURG, OF SAME PLACE.

ROTARY PRINTING-MACHINE.

SPECIFICATION forming part of Letters Patent No. 223,981, dated February 3, 1880.

Application filed August 28, 1879.

To all whom it may concern:

Be it known that I, GUSTAV BISSINGER, of Augsburg, in the Kingdom of Bavaria, have invented new and useful Improvements in Rotary Printing-Machines, which improvements are fully set forth in the following specification, reference being had to the accompanying drawings.

The said invention relates to improvements in and connected with rotary printing-machines, whereby they are more especially adapted for printing illustrations and pictures.

In the accompanying drawings, Figure 1 is a longitudinal sectional elevation of a machine embodying my improvements. Fig. 2 represents the lower inking apparatus by a side elevation, partly in section. Fig. 3 is a similar view, showing a modification of the inking apparatus. Fig. 4 is an end elevation, partly sectional, of the worm-carrying shaft, that transmits certain movements to the ink-distributing rollers. Fig. 5 is a plan view of a portion of the inking apparatus, showing particularly the devices for reciprocating the inking-rollers. Fig. 6 represents, by a part plan and part sectional view, a portion of the rollers of the inking apparatus when removed from their actual positions and placed in peripheral contact in the same plane. Fig. 7 is a plan, and Fig. 8 a longitudinal sectional elevation, of the inking-trough. Fig. 9 is a side elevation, and Fig. 10 an end elevation, of the sheet-delivery apparatus.

Like letters indicate the same parts throughout the drawings.

This machine is designed to operate upon a web of paper, which, in the form of a roll, as A, has its end led in the usual manner to the printing mechanism. It is here shown as passing through a moistening or damping apparatus, B, and thence between two calendering or smoothing rollers, G, and between the surface of the lower type-cylinder, P u, and that of the lower impression-cylinder, D u, whereby it receives the so-called "prime," or first impression, on one side. The paper thence passes partially around the upper impression-cylinder, D o, and between its surface and that of the upper type-cylinder, P o, whereby it receives the so-called "reiteration,"

or second impression, upon its other side. The paper then passes between the two cutting-cylinders S' S², by which it is perforated transversely upon lines that determine the length of the sheets to be formed, which, by means of the two snatching-rollers W' W², are successively torn off from the web. These printed sheets are carried, by means of the tapes 20 21 and the rollers J' J² J³ J⁴ M N' N², over which they pass, to the separator V' V² and to the delivery-apparatus L' L², by which they are laid down upon the piling-tables T' T².

The type and impression cylinders are mounted in bearings in a suitable frame-work, and are geared together, so as to run in unison, by means of toothed wheels, as is common. The cutting-cylinders, which are geared together and provided with the usual cutters, are mounted in the frame-work and driven in unison with the printing-cylinders by means of gear-wheels 7 8 9, the latter being upon the shaft of the upper impression-cylinder, D o. The snatching-rollers W' W² are properly mounted in the side frame, somewhat more than a sheet's distance in advance of the cutting-cylinders, and are geared to and driven from said cylinders by the train 6 6 6, so that said rollers have a slightly faster surface-movement, and hence when they nip the end of the web they operate to advance it rapidly and detach it on the line of perforation, thus forming single sheets and separating them a suitable distance apart to admit of their being delivered separately, so that one shall not interfere with another. The rollers J', J², J³, J⁴, M and N are all driven at proper speed and in unison by the train 5 5, &c.

The tapes 20 run from a lead-roller in front of the cutting-cylinders, under the rollers W' J² J⁴, over the roller M, and return over the roller N² and suitable leading and stretching rollers.

The tapes 21 run from a lead-roller in front of the cutting-cylinders, over the rollers W², J', J³, and M, and return around the roller N' and suitable leading and stretching rollers.

In order to prevent smearing resulting from the set-off from the upper impression-cylinder, an offset web, 22, runs along over said cylinder, and constantly presents a dry surface to

the paper to be printed upon, the said offset web being unrolled automatically from the roll C', passed around the rollers x' y' and around the upper impression-cylinder, and thence 5 around the rollers y' x', and is finally rolled upon the roller C'.

The general arrangement of the machine having been described, I will now proceed to describe more particularly its various mechanisms as improved. Each of the type-cylinders has its own inking apparatus, each apparatus being provided with one ink reservoir or fountain, as F o, and with seven form-inking rollers, a' a² a³ a⁴ a⁵ a⁶ a⁷, said form-inking rollers receiving their supply of ink from their ink-reservoir by means of other rollers—that is to say, in the case of the upper apparatus by composition ink-distributing rollers o' o² o³ o⁴ o⁵ o⁶, metal distributing-rollers m' m² m³ m⁴ m⁵ m⁶ m⁷ 20 m⁸ m⁹ m¹⁰, the metal fountain-roller d, and an additional metal roller, as m¹¹, (see Fig. 1,) which latter roller is omitted in the lower apparatus, as is hereinafter explained. This gives the upper inking apparatus twenty-five, 25 and the lower one twenty-four, rollers in all, which provide the means for accomplishing a very fine distribution of ink.

Although each type-cylinder is shown as having seven inking-rollers, a' a² a³ a⁴ a⁵ a⁶ a⁷, 30 four only need be used, as is illustrated in Fig. 3. The roller o' is provided on its circumference with a screw-formed elevation, as is shown in Fig. 6. The metal distributing-rollers m' m³ and m⁵ m⁶ m⁷ m⁸ m⁹ are each provided with toothed wheels, through which they receive their rotary motion from the wheel R (fast upon the shaft of the type-cylinder) by means of the intermediate wheels, r' r² r³ r⁴ r⁵, and at the same time transmit their 35 40 rotary motion to the composition distributing-rollers by means of peripheral friction.

The fountain-roller d receives its rotary motion by means of the worm S, which is fast upon one end of the transverse shaft 16, that 45 supports the intermediate wheel, r⁴. This worm S engages with a worm-wheel, S', on the shaft S³, which carries a worm-wheel, S², that gears with a worm, S¹, that is fast on the shaft of the fountain-roller d. The fountain is provided with an ink or color doctor, p, that is arranged in such relation to the roller d as to allow the proper quantity of ink to pass and yet free the same from any impurities.

The metal rollers m³ m⁵, and composition rollers o', o⁵, and o³ have, in addition to their rotary motion, a longitudinal or endwise movement, the extent of the latter movement not being alike in all the rollers and not taking place at the same time, whereby the said rollers will 50 arrive alternately at the end of their endwise movement. This endwise movement is effected by means of the pivoted vibrating levers k³ k⁴ k⁵, the ends of which levers play between collars on the shafts of said rollers, receiving 55 their to-and-fro or vibrating motion by means of the eccentric pivot k', Figs. 2 and 5, applied to the upper end of the shaft k², which

shaft is revolved by means of a bevel-gear wheel, S⁶, fast upon the lower end, which engages with a similar wheel, S⁷, on the shaft S³. 70

The levers k⁴, which move the rollers o' o⁵, are fast upon a rock-shaft, 3, and the upper lever, k⁴, has an arm, 2, that is pivoted at 4 to an arm, 1, that is fast to a rock-shaft, 11, that also carries the lever k³, that moves the roller o³. 75 The eccentric pivot k' is linked to the pivot 4 by an arm, 12. The levers k⁵, which move the rollers m³ m⁵, are fast upon a rock-shaft, 13, that is rocked by means of an arm, 15, to which is pivoted a link, 14, that is also hung upon the pivot k'. 80

This arrangement of levers so operates, and the movement of the rollers is such, as to cause the ink to be transmitted to the form-rollers and applied to the type-cylinders in the finest 85 layers possible, whereby a perfectly deep-black covering of the printing-surface is effected without running the risk of unduly coating the fine lines, and thus injuring the finest details of the illustrations as regards their purity. 90

By the arrangement and operation of this inking apparatus it will be observed that the seven form-inking rollers receive the ink equally divided from the one ink-reservoir in connection with them—that is to say, the four 95 form-inking rollers a' a² a³ a⁴ on one side and the three a⁵ a⁶ a⁷ on the other side receive equal quantities of ink by the action of the dividing-roller o⁴, as follows: The ink is taken from the fountain-roller d by the roller m⁹, and thence transmitted, through the roller o³, to the roller m⁸. From the roller m⁸ the ink is equally divided and distributed on one side upon the four form-inking rollers a' a² a³ a⁴ by the roller o² and the intermediate rollers, m⁶ o' m³, and on the other side upon the three form-inking rollers a⁵ a⁶ a⁷ by the roller o⁴ and the intermediate rollers, m⁷ o⁵ m⁵. 100

The uniformity of distribution is effected by the roller o⁴ only taking off, with its spirally-formed elevations i, from the roller m⁸ corresponding stripes of ink, which are transmitted to the roller m⁷. This roller m⁷ being of one-half the diameter of the roller o⁴, the stripes of ink transmitted to the former will not be separated from each other, as they were on the roller o⁴, but they will be placed closely side by side—that is to say, the roller m⁷ will be covered with color uniformly on its entire surface. The spiral stripe of ink remaining upon the roller m⁸, not being taken off by the roller o⁴, will be transmitted to the roller o², and thence to the roller m⁶, in the same manner as described with regard to the transmission from the roller o⁴ to the roller m⁷. 110 115 120 125

The roller o⁴ may have its surface divided by other forms of removed parts; but the spiral form is the most practical, for the reason that it removes and leaves a continuous line of ink, and thus aids a perfect distribution.

I must remark here that in the upper inking apparatus the distributing-rollers are disposed of differently from those used in the lower inking apparatus. The rollers o⁴, m⁷, and o⁵ are 130

placed where the rollers o^2 , m^6 , and o^4 are located in the lower inking apparatus, and vice versa, for the reason that the upper type-cylinder rotates in an opposite direction to the 5 rotation of the lower type-cylinder, on account of the course the printing-paper takes. Consequently the rollers of the upper inking apparatus must turn in an opposite direction to the rollers of the lower inking apparatus.

10 Now, if the roller o^2 were to be arranged above the roller m^8 , it would take away from the latter all inking-color, and would not leave any at all for the roller o^4 , supposed to be arranged below the roller m^8 , and as the fountain should be arranged as in the lower apparatus, and its roller d turn in the same direction, it is also necessary to add the intermediate ink-roller, m^{11} , as shown.

15 One feature of the present invention is 20 found in the peculiar arrangement of the impression and type cylinders, which may be briefly described as consisting in mounting the lower type cylinder on one side of its impression-cylinder instead of vertically below the three other cylinders, as is now commonly done. This admits of the arrangement of the 25 inking apparatus for the lower type-cylinder in exactly the same manner as that for the upper type-cylinder. The position and the arrangement of all the rollers are the same, this being of very great importance, especially with reference to the form-inking rollers, whereby the 30 same distribution of ink is accomplished for both of the impressions—that is, the impressions on opposite sides of the sheet—and consequently produces even work. By means of the sidewise position of the rollers the work of attending to the lower inking apparatus is 35 greatly simplified, since if all the four cylinders—that is to say, the two type and the two impression cylinders—were placed vertically beneath each other, the inking-rollers for the lower inking apparatus would require to be arranged below the type-cylinder, which would 40 render the work of attending to the same very inconvenient. By this arrangement of parts the whole machine may be built of less height, and consequently its upper parts may be more 45 easily reached and less vertical space will be 50 occupied by the machine.

It has hitherto been almost impossible to make use of flat engraved plates or those produced by the well-known galvanic method for rotating printing-machines.

55 One part of the present invention relates to means for adapting such plates to rotating machines, this being of the very greatest importance for printing illustrated newspapers and the like cut-work.

60 In order to carry into practice the printing of illustrations by means of rotating machines, it is necessary to give to the cut or engraved plate a permanent circular bend or curve, so that it cannot afterward change its form. For

65 this purpose the flat galvanic plate or electro-type is bent across a heated cylinder of the form of the type-cylinder, and while it is being so

bent it is cooled by means of any suitable contrivance. The plate, having thus received a permanent circular form, is fitted upon the type-cylinder, and will be as firm as a flat plate in the ordinary printer's press, and there will be no danger of a change in its form occurring afterward.

A further improvement in the rotating 75 printing-machine is particularly shown in Figs. 1, 9, 10 of the drawings, and relates to the construction of the sheet-delivery apparatus. This delivery apparatus consists of a sheet-separator and a sheet-laying device.

80 The sheet-separator consists of the two frames formed by the two sets of shafts v^1 v^2 and v^6 v^7 , having tape-rollers carrying tapes V' V^2 , and by the two vertical levers v^3 v^4 , in which the shafts v^6 v^7 are carried, which levers are united with each other by bent coupling-pieces v^5 and the two tape-shafts v^6 v^7 . 85 Tapes run around the shafts v^1 v^2 and the shafts v^6 v^7 . Oscillating motion is transmitted to the frames by the eccentric tappets v^8 90 and the crank-levers v^9 .

The laying device consists of two separate fly-frames, L' and L^2 , which receive their vibrating motion through the two cranks of the wheel l' and the disk l^2 by means of the rods l^3 l^4 and the levers l^5 l^6 , fitted on their rock-shafts w' w^2 . The sheets carried outward between the tapes 21 22 emerge from the small rollers N' N^2 , and are, in consequence of the 95 rocking or to-and-fro motion of the separating apparatus, led alternately upon the tapes V' , on the left-hand side of the said apparatus, and upon the tapes V^2 , on the right-hand side of the same. The sheets on the right-hand side are laid down upon the table T^2 by the 100 delivering apparatus L^2 , and the sheets on the left-hand side are laid down upon the table T' by the 105 delivering apparatus L' .

Having thus described my improvements, what I claim is—

110 1. The combination, with the two separate series of form-inking rollers and the ink-fountain, of the roller m^8 and the roller o^4 , having a portion of its surface removed or cut away, substantially as described.

115 2. The combination of the type-cylinders and their inking apparatus with the impression-cylinders—that is to say, the two impression-cylinders and one type-cylinder arranged vertically above each other, and the other type-cylinder arranged at the side of its impression-cylinder, while the inking apparatus for each type-cylinder is arranged on the same side of said type-cylinders, all substantially as shown and described.

120 125 3. A rotary printing mechanism wherein one type and one impression cylinder are mounted side by side in, or nearly in, the same horizontal plane, and the other impression and type cylinder are mounted one above the other and in, or nearly in, the same vertical plane with the first-named impression-cylinder, all substantially as described.

130 4. The combination, with a single ink-foun-

tain and two separate series of form-inking rollers, of an interposed roller having a screw formed upon its surface, whereby the ink is divided, and one-half is conveyed to one series 5 of inking-rollers and the other half is conveyed to the other series of inking-rollers, all substantially as described.

5. The combination, with the distributing-rollers $m^3 m^5 o' o^5 o^3$, of the vibrating levers k^3 10 $k^4 k^5$ and rotating shaft k^2 , having eccentric

pivots, whereby said rollers are moved end-
wise to different extents and at different times,
substantially as shown and described.

In testimony whereof I have signed my name
to this specification in the presence of two sub- 15
scribing witnesses.

GUSTAV BISSINGER.
